UNITED STATES PATENT OFFICE.

GEORGE D. BLOSSOM, OF FULTON, NEW YORK.

STOVE OR FURNACE.

SPECIFICATION forming part of Letters Patent No. 378,161, dated February 21, 1888.

Application filed December 9, 1886. Serial No. 221,091. (No model.)

To all whom it may concern:

Be it known that I, GEORGE D. BLOSSOM, of Fulton, in the county of Oswego, in the State of New York, have invented new and useful Improvements in Stoves or Furnaces, of which the following, taken in connection with the accompanying drawings, is a full, clear, and exact description.

This invention consists in an improved construction of a sinuous air-heating conduit extending radially into one side of the fire-pot and formed with sloping sides, and arranged with its base near the base of the fire-pot, and with grate-surface around the base of said conduit, thereby crowding the fire from the center of the fire-pot toward the sides thereof, and at the same time, by direct contact of said conduit with the fire, heating the air circulating through the conduit, which discharges the heated air into the apartment of the building to be heated, thereby obtaining an air-heater which is simple and comparatively inexpensive in construction, superior in its sufficiency over other analogous heaters, and also contributes to the heating capacity of the stove.

In the annexed drawings, Figure 1 is partly an elevation and partly a vertical sectional view of a stove embodying my improvements. Fig. 2 is a horizontal section on line x x , Fig. 1; and Fig. 3 is a vertical transverse section on line y y , Fig. 1.

Similar letters of reference indicate corresponding parts.

A represents the fire-pot, a the grate, and B the subjacent ash-pit, of a stove used for heating buildings. The form of said stove is immaterial to my invention. The fire-pot is the essential part to which my invention pertains.

Into the fire-pot A, I extend a sinuous air-conduit, C, the ingoing portion of which enters the lower portion of the fire-pot from one side thereof, and the outgoing portion lies over the top of the ingoing portion and is extended out through the same side of the fire-pot. This air-conduit is arranged radially in the fire-pot, and is preferably of triangular form in cross-section, with a horizontal partition, b , extending part way inward, as shown in Fig. 1 of the drawings. By the triangular form the sides of the conduit become sloping from the top of the outgoing portion to the base of the ingoing portion of said conduit, and

the base of the inner end or return portion of the conduit is of semicircular form, leaving sufficient grate-room around the base of the air-conduit C to admit the requisite air for producing combustion of the fuel. The sloping sides of said conduit prevent the fuel from lodging thereon and at the same time crowd the heat from the center of the fire-pot outward to the sides thereof, and thus produce greater radiation of heat from the exterior sides of the fire-pot. The receiving end d of the air-conduit C is extended downward and may be either terminated at or near the floor of the apartment in which the stove is located or extended to the exterior of the building to receive fresh air. The discharge end e of the aforesaid air-conduit is extended upward on the outside of the stove to a sufficient elevation to produce a draft through the air-conduit. The air passing through the same is intensely heated by contact with the walls thereof, which are surrounded and in direct contact with the fire in the fire-pot; hence it will be observed that by the combination of the air-conduit C with the fire-pot A, in the manner described and shown, I greatly increase the heating capacity of the stove, and at the same time reduce the grate-surface in such a manner as to economize in the consumption of fuel.

Having described my invention, what I claim as new, and desire to secure by Letters Patent, is—

In combination with the fire-pot, the air-heating conduit C, extending into one side of said fire-pot part way the width thereof, and arranged with a grate-surface around its base, and provided with the horizontal partition b , extending part way the length of the conduit C, and the receiving-pipe d and discharge-pipe e , communicating with said conduit, respectively, below and above the partition b , substantially in the manner described and shown.

In testimony whereof I have hereunto signed my name and affixed my seal, in the presence of two attesting witnesses, at Syracuse, in the county of Onondaga, in the State of New York, this 8th day of November, 1886.

GEORGE D. BLOSSOM. [L. s.]
